UNITED STATES PATENT OFFICE.

HENRY BARTEL, OF MILWAUKEE, WISCONSIN.

PHONOGRAPH.

Application filed July 26, 1920. Serial No. 398,954.

To all whom it may concern:

Be it known that I, HENRY BARTEL, a citizen of the United States, residing at Milwaukee, county of Milwaukee, and State 5 of Wisconsin, have invented new and useful Improvements in Phonographs, of which the following is a specification.

This invention relates to phonographs and is particularly directed to phonographs of 10 the cabinet type in which the machine is housed within a table or cabinet.

Objects of this invention are to provide a phonograph which is so combined with a table, for example a library table, that the 15 table may be used for its ordinary purposes either while the phonograph is playing or at other times; to provide a phonograph so combined with a library table that the parts are readily accessible either for operating 20 the machine, for repairing the parts or for assembly; to provide a phonograph of improved appearance; and to provide a combined table and phonograph of great compactness by first having the phonograph 25 telescopically mounted with reference to the table or otherwise movably mounted so that it may disappear within the table, and second, by securing the requisite length of horn or sounding chamber by extending the horn 30 first in one plane by making an elongated loop thereof, and then in a second plane at right angles to the first.

Embodiments of the invention are shown in the accompanying drawings in which—

Fig. 1 is a perspective view of a combined library table and phonograph, showing the table in closed position.

Fig. 2 is a similar view with a portion of the table open showing the parts of the 40 phonograph mechanism.

Fig. 3 is a plan view of a portion of the table showing one form of my invention.

Fig. 4 is a section on the line 4—4 of Fig. 3.

Fig. 5 is a detail of the removable panel and horn portion.

Fig. 6 shows a modified form of construction, and

Fig. 7 shows a further form.

It is to be noted that the first form of the invention illustrated in the drawings is shown in Figs. 1 to 5, inclusive, and that the second and third modifications, which merely illustrate other possible forms and not all possible forms, will, in assembled

position, look substantially like the structure shown in Fig. 1.

Fig. 1 shows a library table in which there are two main compartments 1 and 2, which house respectively the records and shelves therefor and the phonograph mechanism. Above the compartment 1, an ordinary drawer 3 is located which could be used for any desired purpose. Above the compartment 2, a disappearing top 4 is provided which has a downwardly extending portion 5. In Fig. 2, this top has been moved so that it is slid downwardly behind the phonograph mechanism proper with only the upper portion and a portion of the projecting part 5 showing.

Figs. 3 and 4 show the position of the various parts of the phonograph mechanism within the compartment 2. The usual spring motor 6 is mounted substantially centrally of this compartment below the horizontal partition 7. A shaft 8 extends upwardly through this partition and carries the rotating disk 9. The winding shaft 10 extends outwardly through the front wall 11 of the compartment 2 and is provided with a crank 12 which may be either detachably or foldably joined at 13 with the shaft 10.

The sound conveying portions comprise a reproducer 14 carried by a sound arm 15 which in turn is pivotally mounted at one of the rear corners of the compartment 2. This sound arm communicates with a curved sound chamber or horn 17 and through such portions 17 with the external or flaring outer horn 18. It is to be noted that the horn proper consists of the two portions 17 and 18, that the portion 17 is U-shaped and is arranged substantially in a vertical plane, the portion 18 extending therefrom with its axis substantially at right angles to this vertical plane.

Fig. 5 shows the horn portion 17 as it appears when removed from the phonograph proper. This portion 17 is carried by a removable panel 20 which forms a portion of the horizontal division 7 of the phonograph casing, and also forms the rear portion 21 of such casing or compartment. The horn portion 17 is of substantially U-shape and tapers gradually from the point where it joins the stationary portion 22 of the sound arm to its other end located between the bottom curved portion 23 of this U-shaped horn and the upper portion of its

enlarged end. An opening 24 aligns with the inner edges 25 of the portion 18 of the horn and is joined thereto by a sliding tight-fit joint. The edges 25 may be conveniently 5 lined with felt so as to insure a tight joint between such edges and the adjacent portions of the member 17. A deflecting wall 26 extends from the upper edge of the opening inwardly of the portion 17 and diagonally downwardly. The sound waves, upon 10 striking this deflecting wall, are projected outwardly through the other portion 18 of the horn.

It will therefore be seen that this particular 15 arrangement of the removable panel makes it convenient in assembling and also in repairing the machine as the removable panel, the sound arm, and the portion 17 of the horn may be completely removed 20 from the machine.

When the machine is in use, the top 4 of the compartment 2 may be raised and the record placed upon the disk 9. Thereafter the machine may play either with the top 25 4 open as shown in Fig. 2 or with the top closed as shown in Fig. 1, the sound issuing 30 outwardly through the slatted opening at the front lower portion of the table. The volume of the sound may, of course, be regulated by the adjustment of the slats 19. The top 4 is closed as in Fig. 4 and the handle 12 folded flat against the side of the machine or else completely removed, thereby giving the effect of an ordinary 35 library table which may be of course used in its usual capacity.

In the modified forms shown in Figs. 6 and 7 the removable panel construction is employed in the same manner as in Figs. 40 1 to 5, inclusive.

Fig. 6 shows a form of the device in which the phonograph casing 27 is supported by means of flanges 28 and 29 upon slides 30 and 31, such slides or flanges being provided 45 with rollers so as to minimize the friction. This casing 27 is adapted to slide into the compartment 32 which last compartment corresponds to compartment 2 in the first form of the invention. The casing 27 50 carries the entire phonograph mechanism and is provided in its outer wall 33 with a series of adjustable slats 34.

In order to insure equal movement of the device when it is drawn outwardly, two 55 pairs of links 35, 36 and 37, 38 are provided with the outer link in each pair attached to the rear portion of the casing 27. The rear end of the links 36 and 37 are 60 rigidly attached to a shaft 39 mounted in the rear portion of the table. When either of the links are moved due to the motion of the upper or lower portion of the casing 27, the other pair of links is simultaneously moved by the motion communicated thereto 65 by the shaft 39, thereby insuring equal

movement of the upper and lower portion of the casing 27. These links may be so arranged that when the phonograph casing 27 is in its extreme outward position the links will lock this casing against accidental inward motion by their toggle joint action. In order to cause these links to pass over dead center, an arm 40 is rigidly attached adjacent the lower portion of the shaft 29 and is connected by means of a 70 rod 41 with a handle 42 extending outwardly at the lower front portion of the table. The rod 41 may conveniently be guided through an eyelet 43 secured to the lower portion of the table and may be of 75 such length that when the casing 27 is fully retracted the handle 42 is positioned beneath the forward edge of the table. The winding crank may extend at any desired point from the casing and has been omitted 80 for the sake of clearness.

In this modification, the phonograph is pulled outwardly and a record placed thereon, and the machine started. It may be allowed to play while in the extended position 90 or while in the retracted position.

Fig. 7 shows a further modification of the invention in which the casing 44 of the phonograph is hingedly mounted at 45 adjacent the lower portion 46 of the table. It 95 is adapted to rock inwardly into the compartment 47 and occupy the dotted line position shown in this figure. In order to allow adequate clearance for the casing 44, when it is being swung inwardly or outwardly, the flap 48 is hinged at 49 so that it may extend downwardly in its normal position or horizontally as shown in full lines. When in the horizontal position, it is retained by means of a catch 50, such catch being 100 released by means of a cam 51 operated by a handle extending outwardly from the end of the table. A link 52 is positioned upon each side of the casing 44 and is pivotally secured at 53 to the table. The free end of the link 52 is provided with an elongated slot 54 which cooperates with a pin 55 secured to the casing 44. It will thus be seen that the link swings inwardly to the dotted line position when the casing 44 is swung 110 inwardly, and swings outwardly to the full line position when the casing 44 is swung outwardly to thereby securely support said casing in its extended position.

In this modification the phonograph is 120 adapted to play only when in extended position.

It will be noted that a combined library table and phonograph has been provided in such a manner that the phonograph may be 125 used as desired and that the library table may also be used in its normal capacity. It will also be seen that all of the parts of the phonograph are readily accessible and may be easily assembled during its manufacture. 130

Great compactness is secured by this invention without a sacrifice of desirable acoustic properties.

I claim:

- 5 1. A phonograph including the combination with a supporting frame, of means secured to the frame for rotating a record, a wholly removable panel separately secured to the frame, a sound arm and reproducer
- 10 associated with said removable panel and removable therewith, and an amplifying horn composed of two sections, one of said sections being permanently associated with the frame and the other being associated with said removable panel and adapted to register with the first mentioned section when the panel is in place upon the frame.
- 15 2. A phonograph comprising a main cabinet, a fixed horn portion disposed within the cabinet, means above said horn portion for rotating a record, a removable panel disposed to the rear of said record rotating means and normally supported within the cabinet, and a second horn portion supported
- 20 from the panel and provided above the panel with a sound arm and reproducer in communication therewith, said panel, sound arm,
- 25

reproducer, and horn portion being slidably removable as a unit from said cabinet.

- 30 3. A phonograph comprising the combination with a box-like cabinet, a horizontal shelf therein, and means supported from said shelf for rotating a record, of a wholly removable panel at the rear of said shelf and constituting an extension thereof, an amplifying horn portion permanently associated with the cabinet beneath said shelf, and a second amplifying horn portion of substantially a U-shaped contour associated with the removable panel and provided with an opening registering with said first mentioned horn portion, said second horn portion being of such a character that it can be withdrawn with the panel in a sliding movement through the opening left by said panel without disturbing the means for rotating the record.
- 35
- 40
- 45

In testimony whereof I affix my signature in the presence of two witnesses.

HENRY BARTEL.
